Primary Examiner — Robert M Spear*Assistant Examiner* — Vy Koenig(74) *Attorney, Agent, or Firm* — Weiss & Moy, P.C.; Jeffrey D. Moy; Veronica-Adele R. Cao(57) **CLAIM**

The ornamental design for an electronic cigarette container, as shown and described.

DESCRIPTION

FIG. 1 is a perspective view of a first side of the electronic cigarette container with a tab in a closed position;
 FIG. 2 is a perspective view of the first side of the electronic cigarette container with the tab in an elevated position;
 FIG. 3 is a perspective view of a second side of the electronic cigarette container with the tab in an elevated position;
 FIG. 4 is a perspective view of the first side of the electronic cigarette container with a top section removed extracting the electronic cigarette from the container;

FIG. 5 is a perspective view of a first side of the top section of electronic cigarette container, having a cutaway showing an attachment for securing the electronic cigarette within the top section;

FIG. 6 is a perspective view of a first side of a bottom section of the electronic cigarette container, the other sides of the bottom surface being a mirror image thereof;

FIG. 7 is a bottom plan view of the electronic cigarette container; and,

FIG. 8 is a top view of the electronic cigarette container with the tab in a closed position.

The broken lines in FIGS. 1-5 represent unclaimed environment.
